UNITED STATES PATENT OFFICE.

LEMUEL MORGAN DAVIS, OF LONDON, ENGLAND.

TOOTHEBRUSH.

Application filed November 29, 1924. Serial No. 752,851.

To all whom it may concern:

Be it known that I, LEMUEL MORGAN DAVIS, a citizen of the United States of America, of 10 Prima Road, Stockwell, London, S. W. 9, England, have invented certain new and useful Improvements in Tooth-brushes, of which the following is a specification.

This invention relates to tooth-brushes, and has for its primary object to enable the brush head to be removed from the handle portion at will, and changed or renewed as may be desired.

For this purpose, according to the invention, the stock portion of the brush, i. e. that portion in which the brush head is fixed, is made detachable from the handle-portion and fits slidably in a channelled socket or trough forming a virtual continuation of the length of the handle; the stock, which is adapted to be slid into position against a stop by a movement lengthwise of the socket, being retained therein by a locking device capable of disengagement at will.

One form of the invention is illustrated in the accompanying drawings, wherein Figure 1 is a side elevation, partly in section, of the front portion of the brush with the brush-head (which carries the bristles) locked in position, only the adjacent part of the handle being shewn, and the remaining part being broken off for the sake of convenience. Figure 2 is a similar view, the brush-head being shewn as partly withdrawn from, or partly inserted in, position. Figure 3 is a face view of the brush-head and bristles. Figure 4 is a cross section on the line 4—4 of Figure 1. Figure 5 is a side elevation, partly in section, of the locking device, drawn to a larger scale, and Figure 6 is a top plan view of the same.

Referring to the drawings, the handle 11 of the tooth-brush is provided with a forward continuation in the form of a laterally-flanged, flat-bottomed trough 12 of thin material; the flange 13 at each side of the trough being carried round the forward end of the trough as at 14 so as to constitute a stop for determining the position of the brush-head 15. Each lateral flange 13 is inwardly re-curved (see Figure 4) to fit over the correspondingly rounded lateral edge 16 of the brush-head 15; the end flange 14 being similarly recurved to fit over the rounded front terminal edge 17 of the head; whilst the head itself has a flat back adapted

to slide over and fit snugly against the bottom of the trough 12. In order to ensure both a tight fit and also easy retraction of the head 15, the lateral edges 16, 16 of the head preferably converge slightly, in the forward direction, as shewn in Figure 3.

The locking device for retaining the brush-head 15 in position is preferably constituted by a stud 18 (Figures 5 and 6) which passes through, and is adapted both to turn and to slide in, a hole in the handle 11 (or in the bottom of the trough) immediately beyond the rear end of the head; this stud having at its outer end a thin or flatly-domed head 19 adapted to contact with the back of the trough or handle without projecting appreciably from the surface thereof, and at its inner end a radial and slightly elastic arm 20 adapted to overlie the adjacent end of the brush-head and formed with a hooked or nibbed extremity 21 adapted to snap into engagement with a notch or depression 22 on the upper or front surface of the brush-head 15. When the brush-head is to be withdrawn from its position, the stud 18 is turned so as to free the hooked or nibbed extremity 21 of the arm 20 from the notch 22, and is then pushed or allowed to drop through the hole until the arm 20 lies in a recess 23 provided for the purpose in the surface of the handle 11; whereupon the brush-head 15 can be freely slid out of the trough 12, with the bottom of which the upper surface of the radial arm 20 then lies flush (see Figure 2). The notch 22 may have a leading-in groove (not shewn) to facilitate the engagement and disengagement of the hook or nib 21 from the notch. In order to economize space, the stud may be received in a half-round notch 24 at the adjacent end of the brush-head 15.

To facilitate, during construction, the passing of the stud 18 through the hole in which it fits permanently, the radial arm 100 20 is preferably formed separately from the stud itself and secured thereto, as for example by riveting as indicated at 20^a, after the stud has been inserted in position; whilst, in order to prevent the stud from 105 dropping entirely out of the hole when retracted as in Figure 2, the arm 20 is formed with a pair of lateral wings 25 (Figure 6) whereof the conjoint span is greater than the diameter of the upper end of the hole. 110

In order to avoid risk of an edge of the head 19 of the stud, when in its normal or

locking position (Figure 1), projecting beyond the rear surface of the handle 11 and trough 12 in such manner as to permit of the head 19 catching against the lips or gums of the user, the head 19 is preferably received, as shewn, in a recess 26 (Figure 2) formed on the back of the handle by a rounded annular coaming 27 which projects from said back as indicated. Moreover, in order to facilitate the thorough washing-out of the hole 28 in which the stud 18 is normally received, that portion 29 of the shank which seats itself in the hole is made of larger diameter than the portion 10 to which the arm 20 is immediately attached, so that, when the stud is retracted as in Figure 2, the hole 28 is left open throughout virtually its entire extent; whilst, in order to guide this portion 29 of larger diameter into its normal position in the hole, the shoulder between the portions of the stud having different diameters is made conical or tapering as indicated at 30.

It will be obvious that separate brush heads, respectively carrying various different kinds of bristles (or equivalent elements, such for example as rubber protuberances), can by means of the present invention be interchangeably used with the same handle; a point of considerable convenience and advantage in certain dental cases, as for example where, owing to a septic condition of the mouth, it is desirable to employ brush heads formed, together with the bristles or equivalent elements, of such inexpensive material as to justify an entire brush-head being thrown away each time the implement is used.

I claim:—

- 40 1. A tooth-brush comprising a brush-head, a handle separable therefrom and provided at one end with inturned side and end walls forming a socket adapted to slidably receive the brush-head, said handle being provided with a perforation adjacent the entrance to the socket, and a latch in said perforation, said latch comprising a stud adapted both to turn and to slide in the perforation, a head on the rear end of said stud adapted to engage the handle from the rear, and a spring-arm projecting radially from the front end of the stud and adapted

to engage a depression on the front surface of the brush-head.

2. A tooth-brush as claimed in claim 1, wherein the stud which forms part of the latch comprises in its length two parts of different diameters, namely, a part of larger diameter next the head of the stud adapted to fill the perforation in the handle, and a part of smaller diameter from which the spring-arm projects radially, said part of smaller diameter extending beyond the perforation in the handle when the latch is in locking position.

3. A tooth-brush comprising a brush-head, a handle separable therefrom and provided at one end with inturned side and end walls forming a socket adapted to slidably receive the brush-head, said handle being provided with a perforation adjacent the entrance to the socket, and a latch in said perforation, said latch comprising a stud adapted both to turn and to slide in the perforation, a head on the rear end of said stud adapted to engage the handle from the rear, and a spring-arm projecting radially from the front end of the stud and adapted to engage a depression on the front surface of the brush-head, the stud comprising in its length two parts of different diameter, namely, a part of larger diameter next to the head of the stud adapted to fill the perforation in the handle and a part of smaller diameter from which the spring-arm projects radially, and a tapering portion uniting the two parts of different diameter, said part of smaller diameter extending beyond the perforation in the handle when the latch is in locking position.

4. A tooth-brush as claimed in claim 3, wherein the radial spring-arm is formed with lateral extensions adapted to prevent complete retraction of the stud from the perforation in the handle.

5. A tooth-brush as claimed in claim 1, wherein the brush-head has its lateral edges slightly convergent in the forward direction, and the inturned side walls of the socket on the handle are correspondingly convergent to fit said lateral edges, substantially as described.

LEMUEL MORGAN DAVIS.
